UNITED STATES PATENT OFFICE

CHARLES E. BURDETTE, OF ATHENS, PENNSYLVANIA, ASSIGNOR TO INGERSOLL-RAND COMPANY, OF JERSEY CITY, NEW JERSEY, A CORPORATION OF NEW JERSEY

VENTED MOTOR CASING

Application filed March 18, 1929. Serial No. 347,986.

This invention relates to pneumatic motors, and more particularly to a venting device for maintaining the atmospheric pressure within the motor casing wherein the piston or piston

5 tons of the motor reciprocate.

Another object is to utilize the pressure fluid thus conveyed from the casing as a medium for conveying lubricant to relatively movable surfaces of the motor or of the apparatus actuated thereby.

Still another object is to prevent the conveyance of considerable quantities of lubricant from the casing to the atmosphere.

Other objects will be in part obvious and 15 in part pointed out hereinafter.

The figure in the accompanying drawing is an elevation partly in section of a portable grinder actuated by a pneumatic motor and having the invention applied thereto.

20 Referring more particularly to the drawing, A designates generally the grinder comprising a casing B having a reduced forward extension C to the front end of which may be secured a guard D to partly encircle the working implement, such as a grinding wheel E. To the rearward end of the casing B is secured a handle grip F whereby the machine may be guided and held to the work.

In the form of the construction shown, the 25 interior A' of the casing B forms a reservoir for lubricant and a plurality of radially disposed cylinders G are arranged in the wall of the casing A to which they may be secured in any suitable manner. Within the cylinders G are pistons H which are connected to a crank pin J by means of connecting rods K. The crank pin J may, as shown, form an integral portion of a shaft L which extends through the reduced extension C and

40 has secured to its front end the grinding wheel E. As a convenient means for thus securing the grinding wheel to the shaft, said shaft is shown as having a threaded end O for the reception of a nut P which bears 45 against a flange Q interposed between the nut P and the grinding wheel E.

The pressure fluid for actuating the motor may be introduced into the handle grip F, as for instance, at a boss indicated by R, and 50 its admission into the motor may be con-

trolled by a throttle valve (not shown) adapted to be actuated by a trigger S. Such pressure fluid then passes through a passage T in the casing B to a valve chamber U wherein is disposed a distributing valve V of a well known type and illustrated in this instance as forming an integral portion of the shaft L. The valve V is therefore coaxial with the shaft whereby it is rotated.

Preferably the element forming the valve 60 chamber consists of a bushing W disposed in the extension C and forms a bearing for the shaft.

From the valve chamber U to the cylinders G lead supply passages X, only one of which 65 is shown, and these supply passages also serve to return the exhaust fluid from the cylinders to the valve chamber through which it flows to an exhaust port Y in the extension C and the bushing W. Communication between 70 the passages T and X is controlled by the valve V in a well known manner, as is also the communication between the passage X and the exhaust port Y.

The parts so far described may be of conventional forms and are herein only briefly referred to in order to convey a clear understanding of the invention, its application and the advantages which will follow hereinafter. In devices of the type illustrated it is essential 75 that the motor casing be vented to the atmosphere in order to prevent the upbuilding of pressure of high value in the motor casing and which pressure would otherwise act against the idle ends of the pistons and 80 reduce the effective force of the pressure fluid utilized for actuating the motor.

The ideal construction, of course is a cylinder and piston so machined as to entirely 85 prevent the leakage of pressure fluid from the cylinder past the piston into the motor casing. Such construction however is impractical and when constructed in accordance with the usual practice some pressure fluid usually finds its way from the cylinders past 90 the pistons into the motor casing.

Various methods have heretofore been devised for venting the interior of the motor casing. In certain types of motors this problem may be comparatively simple of solution 95

100

but in motors such as that illustrated where the interior of the motor casing also serves as a lubricant reservoir, the venting of the casing must be accomplished in such manner that the lubricant will not be freely expelled from the casing.

The present invention aims to both provide an avenue of escape for leakage pressure fluid from the casing and also to use such leakage pressure fluid as a medium for conveying lubricant in suitable proportions and with a degree of certainty to movable parts of the machine, as for instance to the shaft and the valve.

5 The result sought is accomplished in a novel manner in the present instance by forming a passage Z in the shaft L with the inlet opening of the passage Z at the end of said shaft and preferably on or near the axis 10 of the shaft L adjacent the crank pin J. The opposite end of the passage Z opens into a transverse passage b in the shaft and said passage b in turn communicates with a groove c in the bushing W and into which the pressure 15 fluid with the entrained lubricant flows during its passage from the casing B. A portion of such lubricant is therefore deposited in the groove c and will lubricate the adjacent portion of the bushing W which in this 20 instance serves as a bearing for the shaft L.

Preferably in the exterior of the bushing W is a passage d which affords communication between the groove c and the forwardmost portion of the valve chamber U wherein the 25 shaft L is journalled forwardly of the valve V. Due to this arrangement the pressure fluid will flow through the passage d after passing through the groove c and convey lubricant to the front end of the valve chamber. 30 However, a port e is formed in the bushing W to afford communication between the passage d and a groove f in the bushing which is 35 in constant communication with the exhaust port Y. By means of the arrangement of the passages through the shaft and the associated elements a free path is provided for 40 any pressure fluid which may find its way into the casing and at the same time the adequate lubrication of the shaft and such elements is assured.

50 By forming the passage Z as described lubricant in only minute quantities will find its way thereinto. This is due to the fact that said passage lies close to the axis of rotation of the shaft and the valve so that when the shaft rotates rapidly the crank pin J will form a void in the lubricant adjacent the inlet opening of the passage Z and such lubricant as will pass therethrough will be in the 55 form of a finely reduced spray which may be readily conveyed by the pressure fluid and deposited on the bearing surfaces of the shaft.

I claim:

60 35 1. A pneumatic motor comprising a cas-

ing, a cylinder in the casing, a piston in the cylinder, a shaft, a crank pin on the shaft connected to the piston, a bearing for the shaft, and a passage in the shaft having its inlet opening adjacent the pin and its outlet opening in the periphery of the shaft through which passage pressure fluid leaking past the piston may be conveyed from the casing to deliver lubricant entrained by such pressure fluid to the bearing.

70 10 2. A pneumatic motor comprising a casing, a cylinder in the casing, a piston in the cylinder, a shaft, a crank pin on the shaft connected to be actuated by the piston, a valve associated with the shaft and rotated thereby for controlling the distribution of pressure fluid to the cylinder, a bearing for the shaft and the valve, and a passage in the shaft opening from the end thereof and adjacent the crank pin for conveying pressure 80 fluid leaking past the piston into the casing from the casing and for conveying lubricant entrained by such pressure fluid to spaced points in the bearing for lubricating the shaft and the valve.

85 90 3. A pneumatic motor comprising a casing having an exhaust port, a cylinder in the casing, a piston in the cylinder, a shaft, a crank pin on the shaft and connected to be actuated by the piston, a valve coaxial with the shaft and rotatable therewith for controlling the admission of pressure fluid to the cylinder and the exhaust of pressure fluid therefrom, a bearing for the shaft and the valve, and a passage opening from the end 100 of the shaft and extending through the shaft and the casing for conveying pressure fluid leaking past the piston into the casing from the casing and for conveying lubricant entrained by such pressure fluid to spaced points in the bearing for lubricating the shaft and the valve.

105 110 4. A pneumatic motor comprising a casing, a cylinder in the casing, a piston in the cylinder, a shaft, a crank pin on the shaft connected to the piston, a bearing for the shaft, a passage in the shaft having its inlet opening in the end of the shaft adjacent the crank pin and its outlet opening in the periphery of the shaft adjacent the upper end 115 of the bearing, and a connecting passage in the bearing leading from the outlet opening to the lower end of said bearing, said connecting passage cooperating with the shaft passage for conveying pressure fluid leaking past the piston from the casing and for conveying lubricant entrained by such pressure fluid and delivering such lubricant to the upper and lower ends of the bearing for lubricating the shaft.

120 125 5. A pneumatic motor comprising a casing, a cylinder in the casing, a piston in the cylinder, a shaft, a crank pin on the shaft connected to the piston, a bearing for the shaft, a passage in the shaft having its in-

let opening in the end of the shaft adjacent the crank pin and its outlet opening in the periphery of the shaft adjacent the upper end of the bearing, a connecting passage in
5 the bearing leading from the outlet opening to the lower end of said bearing, said connecting passage cooperating with the shaft passage for conveying pressure fluid leaking past the piston from the casing and for
10 conveying lubricant entrained by such pressure fluid and delivering such lubricant to the upper and lower ends of the bearing for lubricating the shaft, and an exhaust port in the casing adjacent the lower end of the bearing through which said pressure fluid may escape.

In testimony whereof I have signed this specification.
